CLAIM

The ornamental design for a generator frame, as shown and described.

DESCRIPTION

FIG. 1 is a perspective view of a generator frame showing our new design;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a bottom plan view thereof; and,

FIG. 7 is a top plan view thereof.

The broken lines shown herein are for illustrative purposes only and form no part of the claimed design.

The broken line(s) which define the bounds of the claimed design form no part thereof.
